PHOTOPRINTING SYSTEM AND APPARATUS

Robert Stuart, Forest Hills, Long Island, N. Y.

Application January 27, 1939, Serial No. 253,058

8 Claims. (Cl. 88—24)

This invention relates to photoprinting systems and the apparatus used therewith, in which by optical projection documents are photographed on a band either full size or on a reduced scale and the operation may be reversed in which small photographs may be enlarged. The system relates to photoprinting wheels of the type shown in U. S. Patent 2,081,187, May 25, 1937, in which the subjects to be photographed are continuously fed to a rotating wheel and prints of these subjects are taken off on a continuous band as the wheel rotates. The apparatus comprises a rotating wheel having a plurality of radially spaced chambers, each one of which corresponds to a camera for producing the photographic print. The apparatus is particularly adapted for use where a time exposure in the printing operation is desired and which is determined by the speed of operation of the printing wheel. The system may be applied to print on film but it is also adaptable for printing on photostatic paper.

The objects of the invention and the detailed construction thereof will be more particularly understood from the following specification and the accompanying drawing, in which:

Fig. 1 is a sectional elevation of a form of printing wheel for reproducing documents that may be as large as the original, and

Fig. 2 is a plan view of the printing wheel shown in Fig. 1 with part of the cover removed and showing the paper feeding mechanism.

The photoprinting wheel shown in Figs. 1 and 2 is used for the reproduction of documents either full size or reductions of the original. This comprises a wheel made in two vertical sections and upon one of the sections the documents to be photographed are applied by a conveyor belt and on the adjoining section a continuous paper band is provided which is optically connected with the first section to print the document by a time exposure on the paper band.

The wheel is mounted on the stem 11, supported by the base 12 and is provided with a ball bearing at 14. The wheel is rotated about the stem 11 by the belt wheel 15 and belt 16 connected to motor 17. A cover 81 is supported by the disc 82, fixed on the end of the stem 11. This cover encloses the light tube 83 which is provided with a reflector 84 and through the windows 85 in the cover, light from tube 83 is projected through the aperture 86 of the top wheel upon the document 87 which is carried around the wheel by the conveyor belt 88. Through the optical coupling 89 and 90 the image of the document 87 is projected through the aperture 91 of the lower wheel upon the sensitized pa-

per band 92 and the exposure is continued during the portion of the revolution of the wheel that is represented by the light tube 83. A second light tube may be provided as indicated at 83a for illuminating the document 87. The printing wheel is divided into radial compartments as indicated by the divisions 85a and the top compartment 18 is connected with the lower compartment 19 by the light beam through the aperture 52 in the walls separating these two compartments.

Documents may be automatically fed to the top wheel from the tray 93 by the feeding mechanism 95 delivering one of the sheets 94 to the conveyor belt 88, properly spaced to register with the printing apertures 86 in the top wheel. The document 15 is held in place against the conveyor belt 88 by the rollers 96.

This arrangement may be constructed to reproduce photographs corresponding in size with the original or the prints may be made larger or smaller than the original by varying the diameter of the lower wheel and adjusting the optical system accordingly. The paper band 92, after printing, is developed in the usual way.

Having thus described my invention, I claim:

1. A system for photoprinting comprising a rotating drum, a printing drum associated with said rotating drum, each of said drums divided radially into sections, an aperture in the periphery of each section of both drums, means for exposing a document at each aperture of said rotating drum, a fixed annular light associated with each section of the rotating drum for illuminating the exposed documents, a photo-sensitized printing member in the apertures of the printing drum and means optically connecting said drums to project the image of said documents on the sensitized member of the printing drum.

2. A system for photoprinting comprising a rotating drum, a printing drum associated with said rotating drum, each of said drums divided into corresponding radial sections, an aperture in the periphery of the drums for each section, means for exposing a document at each aperture of said rotating drum, a photo-sensitized member exposed in each aperture of the printing drum, an annular light associated with said rotating drum for illuminating the exposed documents and means optically connecting said drums to project the image of said documents on the photo-sensitized member.

3. A system for photoprinting, comprising a pair of drums in axial alignment, one above the other, said drums divided into radial compartments with an aperture in the periphery for each

- compartment, a window in the wall of each compartment, means for delivery documents to the first of said drums, one document to be exposed at each aperture in the periphery of said drum, 5 a printing sheet exposed at each window of the other drum, a fixed source of light outside said drum arranged to illuminate the document at each aperture as the drum rotates, an optical system transferring the image of the document to the second drum and means for projecting the 10 image from the inside of the drum by reflection through an aperture in the periphery of the drum upon a printing sheet at the corresponding aperture.
- 15 4. A system for photoprinting, comprising a revolving drum with a printing drum attached thereto, said drums divided radially into sections, an aperture in the periphery of each drum, a window in the wall of each compartment of one of said drums, an annular light tube arranged to illuminate the apertures in the periphery through said windows as said drums revolve, means for supplying documents to said drum located one in each aperture, a sensitized band applied to the 20 printing drum and an optical system for printing the picture of the document in each compartment on said band.
- 25 5. A system for photoprinting comprising a pair of drums in axial alignment, said drums being divided radially into compartments and said compartments in one drum being located in register with the compartments in the other drum, an aperture in the periphery of each compartment, a window in the side wall of each compartment of one drum, a fixed annular light tube in register 30 with said windows, the documents to be photoprinted being placed in the apertures of the compartments illuminated by said tube, sensitized paper being placed in the apertures of the other drum, and optical means for transferring, by reflection, the image of the document and printing same upon the sensitized paper in the registering compartment.
- 35 6. A system for photoprinting comprising a drum divided radially into compartments with an aperture in the periphery of each compartment, windows in the side of each compartment, a fixed annular light tube in register with said windows for illuminating the apertures, documents to be 5 photographed placed in said apertures, sensitized paper for each aperture mounted to rotate with said drum and optical means for transferring, by reflection, the image of the document in each compartment and printing same on said sensitized 10 paper as the drum rotates.
7. A system for photoprinting, comprising a fixed stem, a pair of drums rotatably mounted on said stem, means for rotating said drums, said drums being divided radially into compartments, 15 one above the other, means for mounting documents on the periphery of one drum with the side to be printed exposed from the inside of the drum, means for mounting sensitized paper on the periphery of the other drum with the sensitized 20 side exposed from the inside of the drum, windows in the side of the drum having the documents, an annular light tube supported by said stem in fixed relation to said drum for illuminating said documents, and optical means for transferring the 25 image of the document and printing same upon the sensitized paper as the drums rotate.
8. A system for photoprinting, comprising a fixed stem, a pair of drums rotatably mounted on said stem, said drums being divided radially 30 into compartments, one above the other, means for mounting documents on the periphery of one drum with the side to be printed exposed from the inside of the drum, means for mounting sensitized paper on the periphery of the other drum with 35 the sensitized side exposed from the inside of the drum, windows in the side of the drum having the documents, fixed means for illuminating the document in each compartment through said windows and optical means for transferring the image 40 of the document, by reflection, and printing same upon the sensitized paper.

ROBERT STUART.
